ATTORNEY

UNITED STATES PATENT OFFICE.

ROBERT T. GARRETT, OF PHILADELPHIA, PENNSYLVANIA.

TIME-REGULATOR FOR DAMPERS OF FURNACES, RANGES, OR STOVES.

1,111,713.

Specification of Letters Patent. Patented Sept. 22, 1914.

Application filed August 9, 1913. Serial No. 783,870.

To all whom it may concern:

Be it known that I, ROBERT T. GARRETT, a citizen of the United States, residing at the city of Philadelphia, in the county of Philadelphia and State of Pennsylvania, have invented certain new and useful Improvements in Time-Regulators for Dampers of Furnaces, Ranges, or Stoves, of which the following is a specification.

10 My invention relates to means to manually set a time regulator for the damper of a furnace, range or stove to control automatically by a clock-mechanism actuation of means affecting the fire mass of the furnace, 15 range or stove; and in such connection my present invention relates to the particular arrangement of the time regulator for the defined purpose, as hereinafter fully described and claimed.

20 The nature and scope of my present invention will be more fully understood from the following description taken in connection with the accompanying drawings forming part hereof, in which—

25 Figure 1, is a side elevational view of a furnace provided with a time regulated damper and clock-mechanism as a part thereof, suspended from the rafters of a cellar or other room, the time damper regulator being manually set, and then controlled as to its actuation by the alarm-mechanism of the clock, for operating the dampers, to respectively open and close the same and embodying the main features of 35 my said invention. Fig. 2, is a broken sectional front elevational view on the line $\alpha-\alpha$ of Fig. 3, with the face-plate of an ordinary alarm clock removed. Fig. 3, is a vertical sectional view through the clock- 40 mechanism, showing the face-plate, hour and minute hands, the chain and weight winding means and the grooved pulley on the back of the clock secured to the shaft of the alarm-mechanism and over which the

45 cord or chain secured to said pulley is actuated in connection respectively at both ends with the ash-pit and draft dampers of the furnace, as in Fig. 1. Fig. 4, is a front elevational view of a range with a time damper

50 regulator of my invention, shown in application thereto. Fig. 5, is a rear view of the clock, showing the grooved pulley with its stops and the said pulley controlled by the spring controlled shaft of the alarm- 55 mechanism, and also showing the cord at-

tached to said pulley and the draft damper and the opposite end having a hand-hold to manually operate for permitting of the opening of the damper through the setting of said alarm according to the time the 60 chimney or draft damper is to close. Fig. 6, is a broken sectional side elevational view of the range chimney damper in a closed position with the cord from the pulley of Fig. 5, in connection with the damper; and 65 Fig. 7, is an end view in broken section of the grooved pulley, showing the cord and screw for securing to said pulley in the manner, as illustrated, in side view in Fig. 5.

Referring to the drawings with particular reference to Figs. 1-3 inclusive, α is a furnace of ordinary well-known construction having a damper door α^1 , located to one side of the draft-pipe α^2 , to the chimney flue, and having an ash-pit damper door α^3 . 70

b , is a clock suspended, as shown, from rafters b^1 , of a cellar or other apartment in which the furnace is located. The clock as shown is provided with a chain b^2 , carrying a weight b^3 . This chain is for manually winding the main spring controlling the hour and minute hands of the clock and which clock is also provided with an alarm-mechanism b^4 , Fig. 2, having a setting hand b^5 , Fig. 1. This clock represents the well-known Ingersoll or Waltham alarm clock. 75 On the rear of the shaft b^6 , of the alarm-mechanism b^4 , is rigidly mounted a large grooved pulley wheel b^7 , having stop-pins b^{10} and b^{11} , as illustrated in Fig. 5. The 80 shaft b , is provided with a coiled leaf spring b^8 . The said shaft is journaled to a right-angular bracket b^9 , which is secured to the back-plate of the clock b , and with which bracket the stop-pins b^{10} and b^{11} , respectively engage the upper part b^{13} , of the bracket b^9 when the damper is open and the lower part b^{14} , of the bracket b^9 , when the damper is closed. 85

The grooved pulley wheel b^7 , carries a cord b^{15} , as shown. One end of the cord b^{15} , is connected with the ash-pit damper door α^3 , and passes over a series of guide-pulleys b^{17} , depending from the rafters and which cord carries a weight b^{18} , above the 100 connection of the other end of said cord with the draft-damper α^1 . In dotted outline is shown in Fig. 1, the open position of the draft damper. The hook b^{19} , is provided at the opposite end of the cord b^{15} , to attach 105 110

to an eye b^{20} , to the right provided in the ash-pit damper door a^3 , as shown in Fig. 1, for permitting of the opening of the same.

To operate the time regulator under the 5 damper arrangement of Fig. 1, when the draft damper a^1 , is to occupy an open position, it is necessary only to manually operate the cord b^{15} , to set the dampers a^1 and a^3 . The clock is now wound up manually by the 10 weighted chain b^2 , and therewith the alarm-mechanism set by hand to permit the said alarm at a particular hour to go off and to actuate the spring controlled shaft b^6 , carrying the large grooved pulley b^7 , to thereby 15 cause the same to revolve and the stop-pin b^{11} , to engage the bracket b^9 , to thereby hold the said pulley from further movement, at which time the draft damper a^1 , is closed and the ash-pit door damper a^3 , is opened.

20 In Figs. 4 to 7 inclusive, the time damper regulator is illustrated in application to a range in which one end of the cord b^{15} , is attached to the draft regulator damper a^1 , of the chimney flue and the other end beyond its fixed connection with the grooved 25 pulley wheel b^7 , is carried and operated by the spring controlled shaft b^6 , of the alarm-mechanism b^4 , of the clock b . This cord b^{15} , is provided with a hand-hold b^{21} , for drawing the same outward to elevate the regulator damper a^1 , to the extent desired, and at the same time to wind the alarm-mechanism b^4 , of the clock b , at such hour as that the tripping device b^{23} , of said mechanism, 30 as illustrated in Figs. 2 and 3, can cause the

alarm to go off under the action of the wound up main spring of the clock, as will be readily understood. The winding is accomplished manually by the weighted chain b^2 , which chain passes over a sprocket-wheel b^{22} , as illustrated in Fig. 5. The stop-pins b^{10} and b^{11} , respectively, limit the extent of movement of the said pulley-wheel b^7 , of the spring controlled shaft b^6 , of the said alarm-mechanism b^4 , in the winding and 40 also in the reverse movement of the said pulley-wheel, when the alarm is to go off, at a particular selected time.

Having thus described the nature and objects of my invention, what I claim as new 50 and desire to secure by Letters Patent is:—

In a time regulator damper for furnaces, etc., a clock having an alarm-mechanism provided with a spring controlled shaft and a tripping-device, a pulley carried on and 55 operated by said shaft, flexible weighted means connected with said pulley to control the dampers and to permit of winding of said mechanism, a bracket secured to the framework of said clock and said pulley 60 provided with stop-pins to respectively engage different parts of said bracket, substantially as and for the purposes described.

In witness whereof, I have hereunto set my signature in the presence of the two subscribing witnesses hereto.

ROBERT T. GARRETT.
